UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed July 21, 1924. Serial No. 727,210.

To all whom it may concern:

Be it known that I, THOMAS ELLIOTT, a citizen of the United States, residing at Cincinnati, in the county of Hamilton and 5 State of Ohio, have invented certain new and useful Improvements in Railway Cars, of which the following is a specification, reference being had therein to the accompanying drawing.

10 This invention relates to improvements in city railway cars.

The object of the invention is to facilitate the quick entrance and exit of the passengers, particularly in the conditions of 15 crowded passenger traffic, such as now prevails in many of the large cities; and to so co-ordinate the fare payments with such rapid entrance and exit of the passengers as that the payments of the fares will not 20 interfere, but rather work in with and make the more readily possible such quick entrance and exit.

With these important objects in view, my 25 invention consists, essentially, first in providing such railway cars, either newly built cars or those already in existence which may be so modified, with a passenger entrance door near the front, a passenger exit door near the rear and a conductor's station 30 with a fare box located substantially near the middle of the car and at one side thereof, preferably the curb side.

By this arrangement I am enabled to 35 divide the act of fare payments into two periods, one period when passengers who seat themselves in the rear half of the car, after entering at the front end, pass the conductor's station, in which case such passenger will pay within the car just before 40 they take seats, and the other period when the passengers who take seats in the forward portion of the car pass the conductor's station and fare box when they are about to leave the car and are on their way to 45 the exit door; and my invention further relates to a system of passenger management consisting in first receiving the passengers at one end of the car, later discharging the passengers at the other end, 50 dividing the fare payments into two periods, in one of such periods the fares being paid by that portion of such passengers who on entering the car move to the rear thereof, and the other period by that portion 55 of the passengers who remain on enter-

ing in the forward portion of the car, whereby one group of passengers pay immediately on entering and the other group pay just before leaving the car.

This system, as above stated, I carry into 60 effect by means of my organization and co-ordination of the structural features of the car, comprised of the aforesaid front entrance doorway and rear exit doorway, combined with my centrally located conductor's 65 station and fare box.

This arrangement I further improve by 70 preferably making the conductor's station and the fare box transferable from one side of the central portion of the car to the other so that the conductor may position 75 himself in the location most favorable to enable him to better see the movements of the passengers as they enter through and pass out of the entrance and exit doorways.

In some instances, my improved car will 80 have the entrance doors at both sides of the front end and the exit doors at both sides of the rear end, as in the case of so-called double-ended cars, which travel back and forth over their routes without being turned around, but in those cases where what is known as single-ended cars are employed, 85 that is, cars which are turned around at the termini of their routes I provide the entrance door at one side only of the front and the exit door at one side only of the rear end; but in both cases I co-ordinate 90 such entrance and exit doors with this essentially centrally located conductor's station, and in some cases prefer to make such station and fare box transferable from side to side of the car, which transference facilitates the observation of the passengers by 95 the conductor and which also, in the case of cars that are not turned around at the termini of their routes, will result in placing the conductor always on the curb side.

And it will be observed also that if for 100 any reason, such as the requirements of a city ordinance the passengers must enter at the rear end of the car and exit at the forward end, this may be done with my improved car without interfering with the co-operation of the conductor's station at or 105 near the middle of the car, and transferable from one side of the car to the other, with the end doors and without interfering with this system of dividing the fare payments into two periods.

In the accompanying drawings:

Fig. 1 is a plan view of a double-ended car having an even number of windows showing the seating arrangement and my conductor's station in the position it would occupy on either side of the car;

Fig. 2 is a plan view, on an enlarged scale, showing the conductor's station with all the mechanisms in working order;

10 Fig. 3 is a vertical sectional view taken on the line 3—3 of Fig. 2 and looking in the direction of the arrows;

Fig. 4 is a vertical section view of one of the passenger seats;

15 Fig. 5 is an enlarged detail view of the locking mechanisms for retaining the conductor's station and seat in the desired position.

20 In Fig. 1 of the drawings I have shown the relative locations of the conductor's station in a double-ended car, with an even number of windows, such cars having doors on either side at either end and adapted to be reversed at the end of the line. If the 25 car had an uneven number of windows the conductor's position would preferably shift directly across to the opposite side of the car. My invention is equally applicable to a single-ended car or one that has doors only 30 on one side at either end and adapted to be turned around at the end of the line, in which cars the conductor's position would remain stationary. The car is provided with the usual platforms 1 and 2 having 35 doorways 3 and 4, respectively. A passage-way 5 extends from one platform to the other through the center of the car and end seats 6 and cross seats 7 are placed on either side of the passage-way. Near the 40 middle of the car I provide a conductor's station or platform comprising a frame work 8 and floor 9. This platform is adapted to be secured to the floor of the car in any suitable manner. In the present 45 instance I have shown means for removably securing same. To this end brackets 10, having recesses, are secured to the frame work 8. These recesses receive spring-pressed catches 11 suitably mounted in the 50 floor of the car. This means of detachably securing the platform to the floor of the car has been provided in case it is desired 55 to shift the conductor's station from one side of the car to the other, as in the case 60 of double-ended cars, rather than provide two conductors' stations in the same car, in order that the conductor may always be on the curb side which will be advantageous where he has control of the entrance or exit 65 doors or both.

Suitably mounted on the conductor's platform is a stanchion 12 adapted to receive a change tray 13 provided with a metal plate 14 on the under side thereof to strengthen 70 same and secure it to the stanchion. A rail-

ing having a vertical portion 15 anchored to the floor 9 by a suitable floor plate 16 and a horizontal portion 17 coupled to the stanchion 12, as shown at 18, serves to confine the conductor's position and to support the stanchion 12. A railing having a vertical portion 19 secured to the floor 9 by a floor plate 20 and a horizontal portion 21 received by the coupling 18 further serves to support the change tray.

75 A seat for the conductor is provided and comprises a seat proper 22, in the present instance wooden slats, and a supporting frame having a horizontal member 23, a vertical member 24 and a diagonal bar 25 80 connected with the member 24 and the seat 22. The seat with its supporting frame is hinged to the platform or base, as shown at 26, and held in place by spring clips 27, of which there are two. A chain 28 is 85 secured to each of these clips and by pulling on said chain both clips may be simultaneously released, whereupon the seat may be swung over on to the platform, as shown in dotted lines in Fig. 3. This will be convenient in case it is desired to move the platform from one side of the car to the other.

90 A fare box may be mounted on the conductor's station in any suitable manner, as shown at 28.

95 In Fig. 4 I have shown a special form of car seat which may be installed in that portion of the car where it is desired to locate the conductor's station, in order that as much seating space may be retained as possible. This seat has the usual back support 29 to which is secured the back cushion member 30. The seat portion 31 is pivoted to the back member 30, as shown at 32, and a supporting member 33 is pivoted to the forward end of the seat 31. A rod 34 pivotally attached to the member 33, and to a bracket 35, secured to the back support, braces the supporting member 32 and is of such shape that when the seat 31 is folded up against the back the supporting member 33 will rest against the under portion of the seat and be out of the way. By equipping a car with such seat on either side 105 near the middle I will be enabled to utilize the entire seating capacity of the car on the side which is not being occupied by the conductor.

110 It will thus be seen that by the foregoing arrangement I am enabled to rapidly load double-ended and single-ended cars with the entrance and exit doorways both located near the ends of the cars. In the case of single-ended cars it will only be necessary 115 to provide one conductor's station which may be permanently located near the center of that side of the car nearest the curb, while in the case of double-ended cars a conductor's station may be installed on 120

either side of the car near the center or a single station may be used and transferred from one side to the other of the car at the terminus of the line. I have shown one means for carrying out this latter step which will not only enable me to apply my system to cars already in use, but which will leave the cars with practically the same seating capacity as in the old system of 10 positioning the conductor near either end of the car. So far as applicant is aware this system of dividing the collection of the fares into two periods has only been used on cars with central doorways and the expense incident to installing new cars has been an obstacle in the way of its adoption generally, although in some instances the exigencies of the case have necessitated its adoption as the only means of solving the 20 problem of handling the crowded traffic conditions that had to be met. Furthermore, the system requiring the use of a central doorway was not practical on lines where the cars have to be reversed instead 25 of being turned around at the end of the line, in which case exit and entrance doorways must be provided on both sides of the car and use of the central doorways on both sides of such cars is objectionable because 30 too much seating capacity of the cars is utilized.

Referring now to my method, it consists of having all passengers enter at one end of the car and later exit at the other end, in 35 dividing the fare payments into two periods of time between the exit and entrance of passengers, one group of passengers paying their fares immediately on entering the car and passing to the section of the car nearest the exit, the other group of passengers stopping in the section of the car nearest the entrance and later paying their fares on their 40 way to the exit.

I desire to comprehend within my invention such modifications as may be necessary to adapt it to varying conditions.

Having thus fully described my invention what I claim as new and desire to secure by Letters Patent, is:

50 1. A railway car having an entrance doorway near one end, an exit doorway near the other end, a conductor's station located in the central portion of the car, seating facilities between the central station and the entrance doorway and other seating facilities between such station and the exit doorway with a passage way leading from one seating section to the other and past such conductor's station, whereby passengers after 55 entering may be divided into two groups, one in each seating section and whereby also one group will immediately pay on passing the conductor's station, and the other group later pay on passing the conductor's station 60 for purposes of their exit.

2. A railway car having an entrance doorway near one end, an exit doorway near the other end and conductors' stations located on both sides of the car in the central portion thereof, whereby the conductor may always be on the curb side, seating facilities between the central stations and the entrance doorway and other seating facilities between such stations and the exit doorway with a passage way leading from one seating section to the other and past such conductors' stations, whereby passengers after entering may be divided into two groups, one in each seating section, and whereby also one group will immediately pay on passing the conductor's station and the other group later pay on passing the conductor's station for purposes of their exit.

3. A railway car having an entrance doorway near one end, an exit doorway near the other end, and a removable conductor's station adapted to be placed on either side of the car so that the conductor will always be on the curb side, seating facilities between the central station and the entrance doorway and other seating facilities between such station and the exit doorway with a passage way leading from one seating section to the other and past such conductor's station, whereby passengers after entering may be divided into two groups, one in each seating section and whereby also one group will immediately pay on passing the conductor's station and the other group later pay on passing the conductor's station for purposes of their exit.

4. A railway car having an entrance doorway near one end, an exit doorway near the other end, a conductor's station and seating facilities between said doorways, one seat located in the central portion of the car on either side thereof adapted to be folded to provide room for said conductor's station.

5. A railway car having an entrance doorway near one end, an exit doorway near the other end, a conductor's station and seating facilities between said doorways, one seat located in the central portion of the car on either side thereof adapted to be folded to provide room for said conductor's station, and means for detachably securing said conductor's station in position.

6. A railway car having an entrance doorway near one end, an exit doorway near the other end, seating facilities between said doorways, one of said seats in the central portion of the car on either side thereof adapted to be folded to provide an unobstructed floor space at such points, a conductor's station adapted to be removably secured in such floor space and moved from one side of the car to the other when it is desired to have the conductor on a particular side of the car.

7. In a railway car, a conductor's station

comprising a platform, means for supporting a change tray thereon, a seat hinged to said platform, means for securing said seat in operative position, and means for holding said seat over on said platform.

8. The herein described system of managing passenger traffic in a street railway car consisting, first, in admitting the passengers at one end, later in discharging them at the other end, in dividing the fare payments into two periods of time between the entrance and exit of passengers, one payment period being immediately upon the passengers entering and before taking their seats and the other payment period immediately before the passengers leave the car.

9. The herein described system of manag-

ing passenger traffic in a street railway car consisting, first, in admitting the passengers at one end of the car, a part of said passengers immediately paying their fares and passing into the half of the car beyond the place of payment where they remain until ready to leave through the exit doorways at the end of the car opposite to the entrance end, the other part of said passengers remaining in the half of the car adjacent the entrance and later paying their fares as they pass the place of payment on their way to the exit doorways.

In testimony whereof, I affix my signature.

THOMAS ELLIOTT.
